United States Patent Office

Des. 186,481
Patented Oct. 27, 1959

186,481

BOAT

Ray E. Leger, Paramount, Calif.

Application October 30, 1958, Serial No. 53,223

Term of patent 14 years

(Cl. D71—1)

FIG. 1

FIG. 2

FIG. 3

FIG. 4

FIG. 5

Figure 1 is a top plan view of a boat illustrating my new design;

Figure 2 is a bottom plan view thereof;

Figure 3 is an elevational view of a side thereof;

Figure 4 is a front view thereof; and,

Figure 5 is a rear view thereof.

The dominant features of my design reside in the portions shown in full lines.

I claim:

The ornamental design for a boat, substantially as shown and described.

References Cited in the file of this patent

UNITED STATES PATENTS

D. 182,728 Kinzie ----- May 6, 1958
2,666,406 Babcock ----- Jan. 19, 1954